(57) **CLAIM**

The ornamental design for a guitar stand, as shown and described.

DESCRIPTION

FIG. 1 is a front, left and top perspective view of a guitar stand, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is another front, left and top perspective view of the guitar stand in another state.

FIG. 12 is another front, left and top perspective view of the guitar stand in another state; and,

FIG. 13 is another front, left and top perspective view of the guitar stand, wherein the three parts are separated with each other.

The broken lines depict portions of the guitar stand that form no part of the claimed design.

1 Claim, 13 Drawing Sheets
